UNITED STATES PATENT OFFICE.

ARTHUR E. WYGANT AND ARTHUR CHRISTENSEN, OF OAKLAND, CALIFORNIA.

DESIGN FOR A SAVINGS-BANK.

48,921.

Specification for Design.

Patented Apr. 18, 1916.

Application filed March 16, 1915. Serial No. 14,815. Term of patent 3½ years.

To all whom it may concern:

Be it known that we, ARTHUR E. WYGANT and ARTHUR CHRISTENSEN, citizens of the United States, residing at Oakland, in the county of Alameda and State of California, have invented a new, original, and ornamental Design for Savings-Banks, of which the following is a specification, reference being had to the accompanying drawing, forming part thereof.

The figure is a perspective view of a savings bank, showing our new design.

We claim:—

The ornamental design for a savings bank, as shown.

In testimony whereof we affix our signatures in presence of two witnesses.

ARTHUR E. WYGANT.
ARTHUR CHRISTENSEN.

Witnesses:

R. M. OYARZO,
W. A. STOCK.
